UNITED STATES PATENT OFFICE.

CALVIN R. WAID, OF BIRMINGHAM, ALABAMA.

SHAKING, ROCKING, AND DUMPING GRATE.

Application filed October 23, 1925. Serial No. 64,291.

My invention relates to furnace grates suitable for both locomotive and stationary boiler service.

The object of my present invention is to 5 design a grate made up of a plurality of individual sections, each comprising a rocking assembly frame and a series of grate segments interchangeably mounted therein.

It is a distinctive feature of my invention 10 that the grate is designed to interpose a minimum obstruction to the free distribution and flow of air under and through it, and to this end I dispose the sides of the frame at an angle upwardly towards the bridge wall or 15 flue sheet of the boiler so that the frame's transverse members having a pitch in the direction of the flow of air will enable the air to flow freely and almost directly to the fire bed.

It is a further distinctive feature of my 20 invention that both the rocking assembly frame and the segments therein are relatively shallow and substantially wide, to the end that they shall not project deeply below the 25 fire bed and thereby interfere with and impede the flow of the air under the grates and through the fire bed.

It is a further distinctive feature of my 30 invention that the assembly frame shall consist of an elongated substantially rectangular frame, the sides of which are spaced widely apart so as to reduce the number of grate units required to make a grate of given dimensions, and in order to prevent a light 35 frame of this character from warping, I cause the grate segments that are mounted thereon to interlock with its sides and thus form a plurality of intermediate frame braces.

It is a further distinctive feature of my 40 invention that the grate sections and the assembly frame interlock with side tongue and groove joints which are set at an angle following the pitch of the frame sides that will more effectively brace the frame so subjected 45 to strains when being shaken.

It is a further distinctive feature of my 50 invention that the shaker arm is adapted to be interlocked with the assembly frame without the use of bolts or other attachments, the arm being preferably bifurcated so as to straddle a grate segment and notched to interlock with the frame sides between segments which hold it against lateral displacement.

It is a further distinctive feature of my 55 invention that the assembly frame is so designed and so mounted that each section con-

stitutes a dump grate in itself and this enables me practically to dispense with dead grate surfaces under boilers equipped with my invention.

A further distinctive feature of my invention lies in the novel construction of the fire heads of the individual grate bar segments which are of arched zig-zag design, with their ends straight. They are so designed 60 that by varying the thickness of metal in the cross webs the amount of air space per square foot of grate can be varied within reasonable limits, and by lengthening the straight ends 65 the effective width of the unit can be increased 70 or decreased to fit different sized fire boxes, all without change in the standard assembly frame, thus simplifying the adaptation of 75 the invention to various uses and reducing the amount of equipment required to be stocked in order to supply grates for various purposes.

My invention further comprises the novel 80 details of construction and arrangement of parts, which in their preferred embodiment only are hereinafter described and illustrated in the accompanying drawings which form a part of this specification, and in which:

Fig. 1 is a plan view of my assembly 85 frame showing only two complete grate segments mounted therein and also showing the shaker arm in position, the other segments being omitted for the sake of clearness and the side bars or rest bars of the fire box being omitted, as same can be of any standard 90 construction.

Fig. 2 is a cross-sectional view on the line 2—2 of Fig. 1.

Figs. 3 and 4 are respectively fragmental 95 side and plan views of one end of a grate segment.

Fig. 5 is a cross-sectional view taken on the line 5—5 of Fig. 1; and

Fig. 6 is a detail view of one of the interlocking jaws that interlock the shaker arm 100 with the assembly frame.

Similar reference numerals refer to similar parts throughout the drawings.

According to the embodiment of my invention illustrated, I show a typical grate unit which comprises an assembly frame having side members 1 and 2 cast integrally with the end members 3 and 4, the whole constituting a substantially rectangular relatively light casting provided at the center of 110 its ends with trunnions 5 shaped to permit the rotation of the assembly frame within

desired limits. It will be observed that the sides of the frame, though they stand parallel, are pitched at an angle which is better observed in Fig. 2, and the side 2 of the frame is always set towards the point of admission of the air, i. e., towards the front of the boiler. Each of the sides along its inner face carries a series of equi-distantly spaced shoulders 6 which are set opposite each other on the two sides, are of equal thickness, and have the same pitch as the sides. In each side of each of these shoulders I provide a groove 7 which follows the pitch of the shoulder and extends from top to bottom thereof. Each side between the shoulders 6 is reduced at 8 so as to leave pads 9 on each side. Each of the end walls is arched and provided with air vents 10 and 11 and has a zig-zag shape in plan which conforms to the shape of the grate bar segments which will now be described.

Each grate bar segment is a casting comprising end members 12 and 13 which are each provided with side grooves 14 shaped and disposed so that they will interlock by a tongue and groove joint with the shoulders 15 formed by the grooves 7 at the inner edges of the shoulders 6. Each end member carries a pair of spaced upper shoulders 16 and 17 which rest on the top edge of the assembly frame and project over same to form level end portions of the fire heads. These shoulders 16 on one end of the grate which overhang the wall 2 of the assembly frame are made longer than the shoulders 17 which overhang the wall 1 and thus they compensate for the pitch of the grate segment and balance the weight of the fire bed on the assembly frame. The end shoulders 16 and 17 of a grate segment are connected by arched webs 18 which are zig-zag in plan view, as seen in Fig. 1, and these webs are spaced and arranged with their zig-zag walls parallel throughout. The segment parts have the requisite draft for the patterns to be drawn upwardly from the sand and the zig-zag end walls 3 and 4 of the assembly bar maintain a uniform spacing between them and the adjacent grate bar segments.

The segments when interlocked with the frame shoulders 6 will leave a space between them, as seen more clearly in Fig. 1, and I take advantage of the end portions of this space for the convenient mounting of the shaker arm on the assembly frame without the use of bolts, keys, or any like fastening device. As seen in plan view in Fig. 1, the shaker arm is bifurcated and comprises two spaced wide upper arms 19 which merge into narrow bottom legs 20 that are drawn close together and connected by an integral web 21 which spaces them sufficiently for a shaker bar, not shown, to be received between them and connected thereto by a bolt passing through the holes 22. The upper arms 19

are spaced on the same centers as the shoulders 6 and each has its top edge deeply indented or cut away so as to drop below and clear most of the zig-zag portion of the webs 18 of adjacent segments, and each of the upper arms 19 is provided in its end walls, which conform in pitch to the walls 1 and 2 of the assembly bar, with a notch 23 shaped to straddle a shoulder 6. The shaker arm is mounted by inserting its arms 19 upwardly between adjacent pairs of shoulders 6 on each side of the frame and when its notches 23 come into position opposite the shoulders in the assembly bar it is shifted laterally, causing the notches to fit over the shoulders 6. The arms are then shifted to central position on the shoulders, as shown in Fig. 1, and in this position they will stand between the end of the grate segments that are mounted on the sides of shoulders that they are interlocked with and thus the shaker arm is secured to the assembly frame against displacement and yet without any fastenings. The top of the shaker arms is deeply cut away so as to drop it as low as possible below the fire bed thereby to prevent ashes or clinkers accumulating thereon, it being seen in Fig. 5 that it drops below the bottom arch of the adjacent grate bar segments. The segments are of substantially uniform height from top to bottom throughout their arched web portions 18, as seen more clearly in Fig. 2, which reduces to a minimum the amount of metal in the segments and leaves no part of them underhanging the shallow assembly frame. This arch of the fire bed, as the grate bar is rocked, will rub or sift out the ashes and small clinkers from the fire bed resting thereon and the assembly frame has its trunnions so placed that it can rock down and dump without requiring a swinging drop grate or dump grate, as each grate section in itself constitutes a dump grate.

By making the connecting web 21 of the shaker arm triangular we avoid any possibility of it binding on the shaker bar and leaves the segment free to be rocked to the full extent required for dumping, whenever this is desired.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:

1. A grate unit comprising an assembly frame having end trunnions and spaced side walls, opposed shoulders provided on the inner side of said side walls, grate segments adapted to interfit with said shoulders and to

span the frame, and a rocking arm having its top side portions notched and adapted to be received between the shoulders and by lateral movement to engage an opposite pair of shoulders in its notches.

2. A grate unit comprising a substantially rectangular assembly frame having spaced shoulders on the inner wall of its sides, a shaker arm bifurcated at its top and having 10 end notches in its upper ends, said notches being adapted to interlock with said opposed

shoulders, and said ends being spaced on corresponding centers with the shoulders, and grate segments which are mountable on the frame between and on each side of said upper ends of the shaker arm to hold it in position free of any other fastening means than the engagement between its notched portions and the shoulders on the frame. 15

In testimony whereof I affix my signature.

CALVIN R. WAID.
